UNITED STATES PATENT OFFICE.

JOHN K. CHAMP, OF PARIS, KENTUCKY.

DRINKING-CUP.

1,142,304.

Specification of Letters Patent.

Patented June 8, 1915.

Application filed September 23, 1913. Serial No. 791,443.

To all whom it may concern:

Be it known that I, JOHN K. CHAMP, a citizen of the United States, residing at Paris, in the county of Bourbon and State 5 of Kentucky, have invented certain new and useful Improvements in Drinking-Cups, of which the following is a specification.

This invention relates to an improvement 10 in drinking cups.

The primary object of the invention is to provide a drinking cup which may be conveniently carried in the pocket, the construction being such that the bowl of the 15 cup is effectually covered, the device presenting no sharp edges or projections to catch in the clothing.

A further object of the invention is to provide a construction in which the handle 20 of the cup may be readily folded within the bowl portion, the handle being so supported as to rigidly contact with the closure when the same is placed on the bowl, thereby preventing movement of the handle with respect to the bowl.

A still further object of the invention is to provide a resilient handle supporting member which embraces the bowl and forms a reinforcing filler for a beading formed at 30 the edge of the bowl, the beading providing a locking means for the lid member.

A still further object of the invention is to provide a construction in which the handle member is so constructed and supported with respect to the cup that when 35 in its open position, it may be conveniently grasped and the cup supported against tilting, the handle when folded within the cup having its portion which is grasped by the 40 fingers maintained out of contact with the inner wall of the bowl.

For a full understanding of the invention reference is to be had to the following description and accompanying drawing, in 45 which:—

Figure 1 is a transverse sectional view through the cup, showing the handle folded therein. Fig. 2 is a view with the lid removed and the handle extended. Fig. 3 is 50 a transverse section showing a modified form of the handle. Fig. 4 is a perspective view of the handle shown in Fig. 3. Fig. 5 is a detail view of the bracket which supports the handle.

55 Corresponding and like parts are referred

to in the following description and indicated in all the views of the accompanying drawing by the same reference characters.

Broadly, the present invention contemplates the provision of a drinking cup provided with a handle which may be folded within the cup when not in use, the handle being so supported with respect to the cup that it will not contact with the inner walls thereof, there being a lid provided for the cup which may be readily clamped on the cup and effectually supported against displacement.

In the drawings, 10 designates a cup which may be of any suitable design, the 70 edge portion 11 being rolled to form a beading 12. This beading is rolled about a resilient strand of wire 13, whereby the beading is reinforced and at the same time rendered resilient. The lid 14 consists of a 75 disk formed with a flange 15 which is curved, whereby it may engage over the beading of the cup and be effectually held against displacement.

In the form shown in Figs. 1 and 2 the 80 handle 16 is formed with a curved shank 17 which is provided with the finger-engaging loop 18. The handle is supported by a bracket 19 which is secured to the inner wall of the cup adjacent its edge portion. 85 This bracket is formed with apertured ears 20, the end-portion 21 of the shank 17 of the handle being disposed between said ears.

A pin 22 is inserted through the apertured ears and the shank of the handle, forming 90 a pivotal support for the handle. It will be noted that when the handle is raised, as shown in Fig. 2, the curvature of the shank permits the same to be extended over the edge of the bowl whereby it may be conveniently grasped. It will also be noted that when the handle is folded within the cup, it will be so supported that the portions of the same which are engaged by the fingers do not contact with the inner wall of 95 the cup, the shank contacting with the rivet which passes through the opening 23 in the bracket 19 and maintaining the portion 24 of the handle in contact with the lid whereby movement of the handle with respect to the 100 cup is prevented.

In the form shown in Figs. 3 and 4, the handle 25 consists of a shank 26 bent abruptly as at 27, whereby it may engage over the edge of the cup when in its extended 110

position and which maintains the loop 28 in contact with the lid when in its folded position.

What I claim is:—

- 5 1. A drinking cup comprising a bowl, and a handle for the bowl having a shank pivoted to the wall of the bowl in close spaced relation thereto and downwardly spaced within the bowl vertically of said wall, the handle being movable upon its pivot to lie within the bowl and to lie exteriorly thereof, the said shank of the handle being arranged to engage over the rim of the bowl wall when the handle is in position exteriorly of the bowl, the said rim constituting a stop for the handle shank, the handle, when in position within the bowl, being arranged to have its shank rest against the wall of the bowl, whereby the handle proper 20 will be spaced above the bottom of the bowl.

Copies of this patent may be obtained for five cents each, by addressing the "Commissioner of Patents, Washington, D. C."

2. A drinking cup comprising a bowl, a bracket secured to the wall of the bowl inferiorly thereof and downwardly spaced from the rim of the bowl, and a handle for the bowl having a shank pivotally connected 25 to said bracket, the handle being movable upon its pivot to lie within the bowl and to lie exteriorly thereof, the shank of the handle being arranged to engage over the rim of the bowl wall when the handle is in position exteriorly of the bowl, the handle when in position within the bowl being supported above the bottom wall thereof by the engagement of said shank with the bracket.

In testimony whereof I affix my signature 30 in presence of two witnesses.

JOHN K. CHAMP. [L.S.]
